US0D1099232S

(12) **United States Design Patent** (10) Patent No.: **US D1,099,232 S**
 (45) Date of Patent: ** Oct. 21, 2025

(54) HOCKEY STICK BLADE PROTECTOR	5,484,146 A *	1/1996	Loschiavo	A63B 59/70 473/437
(71) Applicant: Bauer Hockey Ltd. , Blainville (CA)	5,520,386 A	5/1996	Sasko	
(72) Inventors: Mathieu Ducharme , Prevost (CA); Candide Deschenes , Saint-Jerome (CA); Gabriel Fedorko , Montreal (CA); Philippe Erhel , Montreal (CA)	5,558,326 A *	9/1996	Adamson	A63B 59/70 473/563
(73) Assignee: Bauer Hockey, LLC , Exeter, NH (US)	5,685,792 A	11/1997	Ruoff	
(**) Term: 15 Years	5,752,695 A	5/1998	Jehan et al.	
(21) Appl. No.: 29/895,585	5,752,698 A *	5/1998	Desroches	A63B 60/56 473/563
(22) Filed: Jun. 23, 2023	5,816,962 A	10/1998	Etersque	
(51) LOC (15) Cl. 21-02	D400,946 S *	11/1998	St. Amand	D21/761
(52) U.S. Cl.	5,941,568 A	8/1999	White, II	
USPC ..... D21/727 ; D21/754; D21/772	6,033,326 A	3/2000	Lee	
(58) Field of Classification Search	6,273,835 B1	8/2001	Battis et al.	
USPC D21/698, 722, 727, 754, 760, 761, 771, D21/772	6,666,479 B1	12/2003	Maddaleni	
CPC A63B 2102/24; A63B 69/0026; A63B 2209/10; A63B 2071/0063; A63B 69/0024; A63B 59/70; A63B 2102/22; A63B 60/00; B26B 29/00; B29K 2995/0049	D506,797 S *	6/2005	Carbonero	D21/754
See application file for complete search history.	6,918,847 B2	7/2005	Gans et al.
